United States Patent Office

Des. 193,110
Patented June 26, 1962

193,110

PORTABLE TANK UNIT FOR DRAINING, STOR- ING AND DISPENSING GASOLINE OR THE LIKE

Ward A. McDonald, 717 Woodcrest Ave.,
Royal Oak, Mich.

Filed Mar. 28, 1960, Ser. No. 59,903

Term of patent 14 years

(Cl. D52—2)

FIG. 1

FIG. 2

FIG. 3

FIG. 4

FIG. 1 is a perspective view of a portable tank unit for draining, storing and dispensing gasoline or the like showing my new design.

FIG. 2 is a front elevational view of the tank shown in FIG. 1.

FIG. 3 is a top plan view thereof.

FIG. 4 is a side elevational view thereof.

The dominant features of the design reside in the portions shown in full lines.

I claim:

The ornamental design for a portable tank unit for draining, storing and dispensing gasoline or the like, as shown and described.
